LOUIS N. LEVINSOHN, OF NEW YORK, N. Y., ASSIGNOR TO EVA LEVINSOHN, OF NEW YORK, N. Y.

SAFETY-RAZOR.

977,889.

Specification of Letters Patent.

Patented Dec. 6, 1910.

Application filed October 22, 1909. Serial No. 523,995.

To all whom it may concern:

Be it known that I, LOUIS N. LEVINSOHN, a citizen of the United States, and a resident of the city of New York, Richmond Hill, 5 borough of Queens, in the county of Queens and State of New York, have invented a new and Improved Safety-Razor, of which the following is a full, clear, and exact description.

10 The invention relates to safety razors, such as are shown and described in the Letters Patent of the United States, No. 931,778, granted to me on August 24, 1909.

15 The object of the present invention is to provide a new and improved safety razor, arranged to accommodate different makes of thin, flexible blades, and permit ready stropping of the blades and adjustment of the latter relative to the guard, for close 20 shaving.

25 For the purpose of accommodating different razor blades, use is made of a pair of clamping plates, and adjustable means for engaging the apertures, slots or notches in 30 different makes of razor blades, at the time they are clamped between the plates. In order to allow ready stropping of the razor blades, use is made of a tubular back hinged to one of the clamping plates and adapted 35 to straddle the same, so as to rise even distances from the outer faces of the plates, and in order to provide for the adjustment of the razor blades for close shaving use is made of a liner interposed between the 40 guard plate and the razor blade.

45 A practical embodiment of the invention is represented in the accompanying drawings forming a part of this specification, in which similar characters of reference indicate corresponding parts in all the views.

Figure 1 is a plan view of the safety razor showing the razor blade in position for shaving; Fig. 2 is a side elevation of the same; Fig. 3 is an inverted plan view of the 50 safety razor showing the razor blade in position for stropping; Fig. 4 is an enlarged cross section of the safety razor, the section being on the line 4—4 of Fig. 1; Fig. 5 is a similar view of the same on the line 5—5 of Fig. 3; Fig. 6 is a plan view of part of the 55 guard plate with a Gillette razor blade in position thereon, together with a liner to space the cutting edge of the razor blade farther from the guard for close shaving; Fig. 7 is a cross section of the same on the

line 7—7 of Fig. 6; Fig. 8 is a perspective view of the liner; and Fig. 9 is a plan view of part of the guard plate with a razor blade thereon having notches at the ends.

The guard plate A and the locking plate B of the safety razor are connected together so that one overlies the other, to permit of clamping the razor blade C between the guard end A' of the guard plate A and the clamping end B' of the clamping plate B. 60 The guard plate A is provided in one side edge adjacent to the guard with a notch and the locking plate B is formed with an offset and provided with a notch in said offset so that when the parts are interlocked as 65 shown in the drawings, the ends of the locking plate lie on opposite sides of the guard plate. In the guard end A' of the guard plate A are formed elongated slots A², A³, ranging lengthwise of the plate A, and in 70 which are mounted to slide studs D, D' projecting into slots B², B³ formed in the clamping end B' of the clamping plate B. The studs D and D' are adapted to engage 75 different makes of razor blades, so as to hold 80 the same against lateral movement, while in position between the ends A' and B' of the plates A and B; for instance, as shown in Fig. 1, the razor blade C is provided with an elongated slot C', through which pass 85 the studs D, D' at the time the razor blade is interposed between the ends A' and B' of the guard plate A and the clamping plate B. In Fig. 6, is shown a Gillette razor 90 blade C², having the usual apertures, of which the end ones are engaged by the studs D and D'; and in the razor blade illustrated in Fig. 9, the ends thereof are provided with notches C⁴ which are engaged by the studs D and D'. Thus by the arrangement de- 95 scribed the studs D and D' engage the razor blades of different makes, by shifting the said studs D and D' in the longitudinal slots A², A³, B², B³, to hold the razor blades against lateral movement during the time 100 they are held between the ends A' and B' of the guard plate A and the clamping plate B.

When it is desired to strop a razor blade, then it is clamped between the stropping ends A⁴, B⁴ of the guard plate A and the 105 clamping plate B, the said end A⁴ being provided with elongated slots A⁵, A⁶, in which are mounted to slide studs E and E', adapted to engage the corresponding slots, apertures or notches of the various makes 110

of razor blades in the same way as above described relative to the studs D and D'. The studs E and E' are adapted to project into corresponding slots B⁵, B⁶ formed in 5 the end B⁴ of the clamping plate B.

By reference to the drawings, it will be noticed that the studs D and D' are centrally disposed on the ends A', B', so that the two cutting edges of the razor blade C 10 are in proper relation to the two sets of guard prongs on the end A'. The studs E and E' are disposed near one side edge of the end A⁴ (see Figs. 3 and 5) so that when the blade C is in stropping position one cutting 15 edge of the blade projects a distance beyond the corresponding edges of the ends A⁴, B⁴.

In order to lock the plates A and B together use is made of a split tube F, provided at one end with an ear F' fulcrumed 20 at F² on the end A⁴ of the guard plate A. By the arrangement described the split tube F may be swung inward, to straddle the ends A⁴, B⁴, so as to lock the plates together at the time a razor blade C is clamped either 25 between the ends A', B' for shaving purposes (see Figs. 1 and 2) or between the ends A⁴, B⁴ for stropping purposes, as indicated in Figs. 3 and 5.

By reference to Fig. 5, it will be noticed 30 that the tube F rises the same distance from the outer faces of the ends A⁴, B⁴, and consequently when the plate C is stropped, the angle at the cutting edge of the blade C is the same during the forward and backward 35 stropping movement of the device on the razor strap.

When it is desired to unlock the plates A and B, it is only necessary for the operator to swing the tube F out of straddling 40 contact with the ends A⁴, B⁴, as indicated in Fig. 3, to allow of taking the guard plate A and the clamping plate B apart by swinging one relative to the other into angular positions, as indicated in dotted lines in Fig. 2.

45 For close shaving, a liner G is interposed between the razor blade and the guard end A' of the guard plate A, as indicated in Figs. 6 and 7, so as to raise the cutting edges of the razor blades farther from the guard 50 prongs, to allow holding the safety razor in a closer shaving position than would be the case if the liner G were removed and the cutting edges of the blades were closer to the guard prongs.

55 The liner G is preferably made U shape, to straddle the studs D, D', thus holding the razor against sidewise movement, the liner being provided at the closed end with a flange G' adapted to be taken hold of by 60 the operator, for placing the liner in position on the end A' of the guard plate A or for removing it therefrom.

It is understood that for shaving purposes

the ends A⁴, B⁴ are used as a handle for manipulating the safety razor, and when 65 the device is employed for stropping a razor blade, the ends A', B' form a handle, taken hold of by the operator for drawing the blade over the strop with the tube F also in contact with the strop.

Having thus described my invention, I claim as new and desire to secure by Letters Patent:

1. In a safety razor, a pair of plates between which a razor blade is to be held, one 75 of the plates being provided with a guard, the plates being each provided with two slots, and studs slidably held in the slots of one plate and in sliding engagement with the slots of the other plate.

2. In a safety razor, a pair of plates having interlocking engagement whereby the plates will lie on opposite sides at opposite ends, the said plates being each provided at each end with a pair of slots, the slots at one 85 end being centrally arranged and the slots at the other end being near one edge, studs slidably held in the slots of one plate and in sliding engagement with the slots of the other plate, and means for securing the 90 plates together.

3. A safety razor, comprising a pair of plates having interlocking engagement, whereby the plates will lie on opposite sides at opposite ends, one of the plates at one 95 end being formed with a guard, and both plates provided with two slots at opposite sides of the center, the slots at the guard end being centrally arranged and the slots at the opposite end being near one edge, studs 100 slidably mounted in the said slots, and a split tube pivoted to one of the plates and straddling the said plates to form a back for the same.

4. In a safety razor, the combination of a 105 guard plate, a razor blade, and a detachable liner in the form of a plate interposed between the guard plate and razor blade to space the blade from the guard.

5. In a safety razor, the combination of a 110 razor blade, a guard plate, a clamping plate, between which and the said guard plate the said blade is clamped, studs held on one of the said plates and engaging the said razor blade, and a detachable U-shaped liner plate 115 interposed between the said guard plate and the said razor blade to space the blade from the guard, the liner plate straddling the said studs.

In testimony whereof I have signed my 120 name to this specification in the presence of two subscribing witnesses.
